UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

TIE PLATE.

Application filed April 21, 1924. Serial No. 707,957.

To all whom it may concern:

Be it known that I, HAROLD G. WARR, a citizen of the United States, residing at Park Ridge, in the county of Cook and

5 State of Illinois, have invented certain new and useful Improvements in Tie Plates, of which the following is a specification.

My invention relates to devices for resisting the longitudinal creeping movement of 10 railroad rails and has for its primary object the provision of an improved arrangement of such devices with relation to each other whereby an additional area of a cross tie is made effective for resisting said creeping 15 movement.

A more specific object of the invention is to provide a tie plate of improved construction adapted, when in its normal position between a railroad rail and a cross tie, to 20 provide an abutment adapted to receive a portion of the creeping pressures exerted by a rail anchor, of the general type intended to bear against a vertical face of the tie, and transmit said creeping pressures to the tie 25 at points remote from the said vertical face of the tie.

Another object of the invention is to provide a tie plate which is so constructed and attached to a cross tie that when the plate is 30 used in connection with a rail anchor of the character above mentioned, it will tend to rotate during the presence of creeping pressure on the rail so as to effect a shackle grip on opposite edges of the rail base and 35 thereby transmit a portion of said creeping pressure directly from the rail to the means for attaching the tie plate to the tie.

Another object is to provide a tie plate which may be made to correspond in length, 40 thickness and weight to the various tie plates now in general use and which at the same time may be made of sufficient width to extend to the opposite side faces of the cross tie without waste of material in its manufac- 45 ture.

A further object is to provide a tie plate with ribs adapted to be embedded in the tie, which ribs are so formed as to permit a rotational movement of the anchor but resist 50 displacement thereof longitudinally of the rail, so as to permit the tie plate or its attaching means, as the case may be, to take

a shackle hold on the rail and at the same time provide additional tie engaging means for resisting longitudinal movement of the 55 rail.

The creeping pressure of railroad rails has a tendency to embed certain types of rail anchors (having relatively small tie engaging surfaces) into the upper edge of the tie, 60 thereby damaging the tie and impairing the effectiveness of the anchor. This condition is particularly prominent in situations where tie plates are interposed between the tie and the rail because the tie plates raise 65 the anchors with relation to the adjacent cross ties and thereby further reduce their tie engaging surfaces.

One of the specific objects contemplated by this invention is to overcome the above 70 mentioned and other incidental objections to the use of rail anchors of the above character by providing a tie plate of improved construction which provides an abutment for such anchors and distributes the pressure from said anchors to the upper surface of the tie. The invention is illustrated in two preferred embodiments in the accompanying drawings wherein

Fig. 1 is a plan view of a tie plate constructed and arranged in accordance with 80 my invention to transmit a portion of the creeping stresses of the rail to points remote from the vertical edge of the cross tie.

Fig. 2 is a face view of the arrangement 85 and construction shown in Fig. 1, the rail base being shown in section for the purpose of clearness.

Fig. 3 is a side view of the construction and arrangement shown in Figs. 1 and 2. 90

Fig. 4 is a plan view, on a reduced scale, of a metal bar from which the tie plates shown in the preceding figures are sheared.

Fig. 5 is a view similar to Fig. 1 showing another embodiment of my invention. 95

Fig. 6 is a face view of the embodiment shown in Fig. 5 and

Fig. 7 is a detail view in perspective of the tie plate shown in Figs. 5 and 6.

Referring first to Figs. 1 to 4 inclusive of the drawings: 10 designates a railroad rail, 11 a cross tie on which the rail is supported, 12 a rail anchor secured to the rail, and 13 a tie plate made in accordance with

one embodiment of my invention interposed in its normal operative position between the rail and cross tie.

The rail anchor herein shown is a one piece device adapted to bear against a vertical face of the cross tie 11 and consists of a bar formed at one end with a jaw portion 14 adapted to grip the upper and lower surfaces of the rail base and provided at the other end with an upturned portion 15 providing a shoulder which engages the opposite edge of the rail base to prevent movement of the anchor in a direction to loosen the grip of said jaw on the rail. This specific type of anchor device, by reason of its relatively small tie abutting area, has been illustrated for the purpose of emphasizing certain advantages obtained by this invention. It will be obvious, however, that the invention is not limited in its usefulness to anchor devices of the specific construction illustrated, but may be used to an advantage with various specific forms of anchor devices adapted to abut against the vertical face of a cross tie to resist longitudinal creeping movement of the rail.

Rail anchors of the above character having relatively small tie abutting area have a tendency to cut away the upper edge of the tie, when the rail is subjected to a creeping pressure, and thereby so damage the tie as to reduce its life and also reduce the effectiveness of the anchor. This tendency is increased when a tie plate is used, since the insertion of the tie plate in the usual manner between the rail and the tie raises the rail with relation to the cross tie and therefore reduces the tie bearing area of the anchor attached to the rail.

With my invention such objections are overcome by arranging the tie plates so that one of the edges coincides with the vertical face of the tie and thereby provides a metallic abutment for the anchor device adapted to transmit a portion of the creeping pressure of the rail to the tie plate attaching means at points remote from the vertical face of the tie.

The tie plate 13 shown in Figs. 1 to 4 inclusive, is preferably substantially flat on its top and bottom surfaces and is secured to the tie by means of spikes 16, 16^a and 17, 17^a arranged on opposite sides of the rail. The spike openings 18 in the tie plate are preferably made slightly larger than the spikes so that the tie plate may shift to a slight angular position, as shown in Fig. 1. The tie plates are preferably sheared from a flat bar B on Z-shaped lines C—D (Fig. 4) so that tie plates of the usual length and thickness may be formed to extend to opposite faces of a cross tie without using a greater amount of metal than is required to manufacture a flat tie plate of the usual form and weight now in general

use. By providing the plate 13 with Z-shaped edges the tie plate and the anchor device engage each other at one side only of the rail. With such an arrangement, the creeping pressure of the rail tends to rotate the plate and thereby force the diagonally disposed spikes 16 and 17^a into gripping engagement with the opposite edges of the rail base, whereby the vertical face of the tie 11 is relieved of that portion of the creeping pressure which is transmitted to the tie by reason of the shackle hold of the spikes on the rail base and also relieves the vertical face of the tie of that portion of the creeping pressure transmitted directly to the edge of the tie plate.

The summary of the operation is as follows: The rail anchor 12 is applied to the rail 10 in a usual manner so as to bear against the vertical face of the tie 11. The tie plate 13 is then positioned between the rail and the tie so as to extend to opposite faces of the tie 11, and is attached to the tie with a suitable number of spikes which pass through the tie plate and also engage the rail base. When the rail 10 is subjected to creeping pressure in the direction indicated by the arrow in Fig. 1, the pressure is transmitted to the vertical face of the tie and to the edge of the tie plate 13. The portion of this pressure transmitted to the edge of the tie plate 13 is transmitted to the several attaching spikes and effects a rotary movement of the tie plate which brings the diagonally disposed spikes against the rail base to effect a shackle grip thereon.

It will also be observed, that the configuration of the tie plate makes it possible to apply anchor devices in such positions as to bear against either or both faces of the tie without affecting the rotation of the plate or the shackle hold of the diagonally disposed spikes 16—17^a as above referred to.

In Figs. 5 to 7 inclusive, I have illustrated another embodiment of my invention, in which the tie plate 19 is formed on its upper surface with shoulders 20—20 adapted to engage opposite edges of the rail base, and is formed on its bottom surface with circular ribs 21, 22, 23 and 24. The rib 21 is preferably arranged centrally of the plate 19 and the other ribs 22, 23 and 24 are disposed concentric thereto. The ribs embed themselves in the upper surface of the tie and thereby increase the tie gripping area of the tie plate and at the same time permit the tie plate to rotate freely during the presence of creeping pressure. The rotational movement of the tie plate brings the diagonally opposite ends 20^a—20^a of the shoulders 20 into engagement with the opposite vertical edges of the rail base so as to effect a shackle hold thereon when the rail is subjected to creeping pressure. In

other respects the tie plate construction and the arrangements shown in Figs. 5 to 7 inclusive may be and preferably are the same as those shown in Figs. 1 to 4 inclusive.

5 It will also be apparent that one of the shoulders 20 of the tie plate shown in Figs. 5 and 7 may be omitted if desired and such plate positioned with the shoulder engaging either side of the rail base. With such arrangement it will be noted that the edges of the tie plate providing the abutment for the anchor devices will be in the same position as that shown in Figs. 5 to 7 so that the jaw portion of the anchor may be driven 10 upon the inner or outer flange of the rail as may be desired. Another advantage presented by tie plates of my configuration and particularly the flat plate shown in Figs. 1 to 4 inclusive is that it may be readily inverted and when so applied provides an abutment for the jaw portion of an anchor applied to the opposite side of the rail, such for example as may be desirable when applying anchors to the outside of running rails 25 having guard rails disposed along their inner side.

With the tie plate construction shown in Figs. 5 to 7 inclusive, the ribs on the under surface of the plate become embedded in the tie, thereby relieving the spikes from a portion of the creeping pressure, the creeping pressure being distributed over a larger area of the upper surface of the ties by means of the embedded ribs 21, 22, 23 and 24. 30 The creeping pressure on the rail imparted to the edge of the tie plate through the rail anchor 12 tends to rotate the plate about its central point, thereby bringing the opposite ends of the shoulders on the upper surface 35 of the plate into gripping engagement with the edges of the rail base and thereby transmits a portion of the creeping pressure of the rail directly to the tie 11 through the several ribs on the under surface of the tie 40 plate and the attaching spikes. The spike openings are made of suitable size to permit the desired rotational movement.

While I have illustrated two specific embodiments of tie plates in connection with 50 certain other specific devices for illustrating the operation and utility of my invention, it will be obvious that further modifications of the tie plate may be made and that various other forms of rail anchors may be 55 used in connection with such plates without departure from the spirit of the invention. I therefore wish it understood that my invention contemplates all such modifications in construction and arrangement as 60 come within the scope of the appended claims.

I claim:

1. The combination of a tie plate interposed between a rail and a cross tie, and a 65 rail anchor secured to the rail and adapted

to abut against a vertical face of the tie; said tie plate being secured to the tie in position to abut against said anchor, whereby creeping movement of the rail imparts a rotary movement to the tie plate.

70

2. The combination of a rail anchor attached to a rail in position to bear against a vertical face of a cross tie and a tie plate interposed between the rail and the upper face of the tie; said tie plate being provided with a projection which extends at one side of the rail to said vertical face of the tie to provide an abutment for said rail anchor.

75

3. The combination of a rail anchor attached to a rail in position to bear against a vertical face of a cross tie and a tie plate interposed between the rail and the upper face of the tie; said tie plate being formed with a substantially Z-shaped edge to provide a projection which extends at one side of the rail to said vertical face of the tie to provide an abutment for said rail anchor.

80

4. The combination of a rail anchor attached to a rail in position to bear against a vertical face of a cross tie and a tie plate interposed between said rail and the upper face of the tie; said tie plate being formed with oppositely disposed substantially Z-shaped edges to provide projections which extend to opposite vertical faces of the tie, 90 for the purpose described.

85

5. The combination of a rail anchor attached to a rail in position to bear against a vertical face of a cross tie and a tie plate interposed between the rail and the upper face of the tie; said tie plate being formed with oppositely disposed substantially Z-shaped edges to provide projections which extend to opposite vertical faces of said tie, whereby the creeping pressure of the rail transmitted to either of said projections imparts a rotational movement to 100 said tie plate for the purpose described.

105

6. The combination with a rail anchor attached to a rail in position to bear against a vertical face of a cross tie, of means for transmitting a portion of the creeping pressure from the rail to points of the tie remote from the said vertical face thereof comprising a tie plate interposed between the rail and the upper face of the tie in position to abut against the rail anchor; the edge of the plate adjacent said anchor being formed with a projection, whereby the engagement between said plate and anchor is 110 confined to points at one side of the vertical center of the rail.

115

7. A tie plate formed on its bottom surface with ribs adapted to be embedded in the tie to prevent movement of the plate longitudinally of the rail, but which permits rotational movement of said plate.

120

8. A tie plate formed on its bottom surface with curved ribs adapted to be embedded in the cross tie, whereby the said 130

plate when in its normal operative position has capacity for rotational movement but is held against movement longitudinally of the rail.

5 9. A tie plate formed on its bottom surface with curved concentrically disposed ribs adapted to be embedded in the cross tie, whereby the said plate when in its normal operative position has capacity for rotational movement but is held against movement longitudinally of the rail.

10. A tie plate formed on its upper surface with abutments for opposite edges of a rail and provided on its bottom surface with curved concentrically disposed ribs adapted to be embedded in the cross tie, whereby the said plate when in its normal operative position has capacity for rotational movement but is held against movement longitudinally of the rail.

15 11. A tie plate formed on its upper surface with abutments adapted to bear against opposite edges of a rail base and formed on its bottom surface with curved concentrically disposed ribs adapted to be embedded in the tie; said plate being formed with corner portions which project to the opposite vertical faces of the said tie.

20 12. A tie plate formed on its upper surface with abutments adapted to bear against opposite edges of a rail base and formed on its bottom surface with curved concentrically disposed ribs adapted to be embedded in a tie; the end portions of said plate being normally of less width than the tie on which

it is supported and the plate being formed with a corner projection which extends to a vertical face of the said tie.

13. A tie plate formed on its upper surface with abutments adapted to bear against opposite edges of a rail base and formed on its bottom surface with curved concentrically disposed ribs adapted to be embedded in a tie; said plate being formed with diagonally disposed corner portions which project to the opposite vertical faces of the said tie.

14. The combination of a rail anchor adapted to be secured to a rail in position to bear against a vertical face of a cross tie, and a tie plate positioned between said rail and said tie; a portion of said plate being normally less in width than the width of the tie on which it is supported and said plate being provided with a projection which extends to said vertical face of the tie to provide an abutment for said anchor.

15. The combination of a rail anchor adapted to be secured to a rail in position to bear against a vertical face of a cross tie, and a tie plate formed on its under surface with means adapted to be embedded in the tie; a portion of said plate being normally less in width than the width of the tie on which it is supported and said plate being formed with a projection which extends to said vertical face of the tie to provide an abutment for said anchor.

HAROLD G. WARR.
